CLAIM

The ornamental design for a vertical post for a scroll saw, as shown and described.

DESCRIPTION

FIG. 1 is a left side perspective view from the front of my new design of a vertical post for a scroll saw;

FIG. 2 is a left side elevational view of my design;

FIG. 3 is a right side elevational view of my design;

FIG. 4 is a front elevational view of my design;

FIG. 5 is a rear elevational view of my design;

FIG. 6 is a top plan view of my design; and,

FIG. 7 is a right side perspective view from the rear of my new design.

In the attached drawings, any broken line illustration is not part of the design sought to be patented.
